BYPASS WELL PACKER

Mordica O. Johnston, Glendale, Wilbur F. Bettis, Montrose, and Frank E. O'Neill, Glendale, Calif., assignors, by mesne assignments, to Johnston Testers, Inc., Houston, Tex., a corporation of Texas

Application January 11, 1955, Serial No. 481,078

6 Claims. (Cl. 166—130)

This application is a continuation-in-part of our co-pending application Serial No. 75,562, filed February 10, 1949, now abandoned. The invention relates to well packers, and more particularly, pertains to a well packer having a bypass passageway therethrough adapted to be closed by a valve mechanism.

It is common practice to set packers within well cases in order to pack off an area of the casing occurring beneath the packing for a desired purpose. In view of the fact that the outside diameter of the packing element has a relatively close fit within the well casing, it is necessary to provide a bypass valve structure which will permit the displaced fluid within the well casing to pass through the packer as it is being lowered in the well. This insures that the packer may be lowered rapidly through its said position, and also insures that when the packer is to be released from its said position, the fluid seal will be broken so that the head of liquid above the packer will pass downwardly through the packer and tend to dislodge the packer sleeve from its set position. It has also been found that when a plurality of packing rings are used in place of a continuous sleeve packer, there is a greater possibility of maximum contact of the packer unit with the casing, and thus a better seal will be created.

It is the principal object of the present invention to provide a multiple ring packer of the bypass type which may be easily locked to hold the bypass valve in its open position, and may easily be manipulated, when disposed at a position of setting to release the valve to permit closing thereof and allow the packer structure to be anchored in a well casing and set at a desired position.

The present invention contemplates the provision of a multiple ring packer structure mounted on a central tubular mandrel suspended from a string of pipe in a well, and means adapted to be manipulated to anchor the packing at a desired level in the well casing, and thereafter release a bypass valve, whereby the bypass valve may be closed and the weight of a string of pipe may be disposed upon the packer.

A preferred form of the invention is described in the following detailed specification and illustrated by way of example in the accompanying drawings, wherein:

Fig. 1 is a sectional view of the upper portion of the packer constructed in accordance with the principles of the invention.

Fig. 2 is a sectional view of the intermediate portion of said packer structure.

Fig. 3 is a view of the lower portion of the packing structure.

Fig. 4 is a perspective view of the structure of the lock mechanism per se.

Fig. 5 is a fragmentary view in partial longitudinal section, showing a modification in the form of the packer.

Fig. 6 is a transverse sectional view taken on line 6—6 of Fig. 5.

Fig. 7 is a transverse sectional view taken on lines 7—7 of Fig. 5.

2

Referring now to the drawings, and more particularly to Fig. 1 thereof, 10 indicates a sliding head which is formed with a central bore 11 therethrough. The upper end of the bore communicates with a tapered thread box 5 section 12 adapted to be connected to the lower end of the well string. A pair of longitudinally extending splines 15 extend inwardly from the inner wall of the member 10 intermediate the ends thereof. A pair of diametrically opposed grooves 14 are defined by the longitudinally extending splines 15. As can best be seen in Figure 4, the lower ends of the spline 15 terminate in an inclined face 15a. A relatively narrow spline extension 15b extends downwardly from the face 15a adjacent the high end thereof.

15 An upper mandrel section 16 is slidably mounted within the sliding head 10 and has formed at its upper end a locking head 17. The locking head 17 has a pair of longitudinally extending grooves 18 formed therein, the grooves 18 being adapted to receive the splines 15. The portions 19 between the longitudinally extending grooves 18 form keys which are slidably received within the grooves 14 formed in the member 10. A pair of recesses 20 are formed in the outer surface of the locking head 17, one adjacent each of the grooves 18. The recesses 20 each have a longitudinally extending face 21 and an inclined surface 22 at right angles thereto. The upper end of each of the inclined surfaces 22 being located closely adjacent to one of the longitudinally extending grooves 18, the inclined cam surfaces 22 are inclined at approximately the same angle as the cam surfaces 15a formed on the spline members 15. During the running in of the tool, the elements of the locked assembly are initially set so that the downwardly facing inclined surfaces 15a on the splines 15 are resting on the upwardly facing incline surfaces 22 of the locking head 17, and the spline extensions 15b are received within the grooves 18 formed in the locking head 17.

40 A valve sleeve 23 is slidably mounted upon the upper mandrel section 16. The valve sleeve 23 has a central cylindrical bore 24 through which the upper mandrel section 16 extends. The upper end of the valve sleeve 23 is formed with a threaded extension 25 which is threaded into the threaded end 13 of the sliding head. The lower end of the valve sleeve 23 has a cylindrical extension 26 which is smaller in diameter than the main body of the sleeve. A shoulder 27 is formed in the upper end of this extension. Against this shoulder and around the portion 26 of the valve sleeve is a non-metallic seal ring 28 here disclosed as being substantially square in cross-section. Mounted directly below said seal ring and upon the extension 26 is a removable valve seat 29. This seat has an outside diameter substantially agreeing with the normal outside diameter of the sealing ring 28 and is formed with a downwardly and inwardly tapered valve 55 face 30. A threaded length 31 is formed at the end of the extension 26 and receives a nut 32. The nut 32 is cylindrical and has a smooth outer surface. An annular square groove 33 is cut around the inner wall of the bore 24 of the valve sleeve 23 and carries a packing ring 34 here shown as being of the chevron type.

60 Mounted upon the upper mandrel section 16 and below the valve sleeve 23 is a tubular packer sleeve 35. This sleeve is of a diameter substantially greater than the diameter of the mandrel 16. At opposite ends of the sleeve 65 inwardly extending lugs 36 are formed which are spaced from each other and which have inner arcuate faces agreeing with the outside diameter of the mandrel 16. The spaces between the lugs 36 provide fluid passageways through which a free circulation of fluid may flow when the by-pass valve is open. The lower end of the sleeve 35 is formed with an enlarged portion 37 which provides

an upwardly presented shoulder 38. A retaining nut 39 rests against this shoulder and has a central opening 40 through which the packer sleeve 35 extends. The upper end of the packer sleeve 35 is formed with an externally threaded portion 41 which extends into a threaded bore at the lower end of a valve seat element 42. Communicating with the threaded bore 41 is a smaller smooth bore 43. A shoulder 44 occurs at the juncture between the threaded bore and the smooth bore and against which shoulder the upper end of the packer sleeve 35 abuts. The bore 43 is of a diameter to accommodate the nut 32 carried upon the valve sleeve 23. At the upper end of the valve seat element 42 is an enlarged bore 45 which accommodates the seal ring 28 and forms a fluid-tight seal therewith. Between the large bore 45 and the smaller bore 43 is a tapered valve seat 46. This valve seat is engaged by the tapered face 30 of the valve 29.

Mounted upon the valve sleeve 35 are a plurality of separate packer rings 47. These rings are preferably made of rubber and are spaced apart by intermediate metal washers 48. The rings are held between the lower face 49 of the valve seat element 42 and the upper face 50 of the retaining nut 39.

The lower end of the retaining nut 39 has a reduced threaded portion 51 which extends into the threaded bore 52 of a slip cone 53. The upper end of the slip cone 53 is cylindrical and tubular and has a central bore 54 which accommodates the enlarged portion 37 of the packer sleeve 35. At the lower end of the cone 53 is a series of circumferentially dovetailed grooves 55 having downwardly and inwardly inclined faces 56. These grooves accommodate slips 57. Intermediate the grooves 55 and formed longitudinally of the slip cone 53 are fluid passageways 58. A central threaded bore 59 occurs at the lower end of the slip cone 53. The upper end of this bore receives the externally threaded lower end of the upper mandrel section 16. The lower end of this bore receives the externally threaded section of a lower mandrel section 60. A central passage 61 is formed through the upper mandrel section and a longitudinally aligned passageway 62 is formed through the lower mandrel section.

Mounted upon the lower mandrel section 60 is a cage sleeve 63. This sleeve is free to slide upon the lower mandrel section 60 and carries a slip rein ring 64 provided with pivot screws 65 which pass through openings in the lower ends of slip reins 66. The slip reins 66 receive pins 67 at their upper ends by which they are pivotally connected to the lower ends of the slips 57. Thus, when the sleeve 63 is reciprocated upon the mandrel 60 the slips 57 may move up and down with relation to the inclined faces 56 of the cone 53 and will thus move inwardly and outwardly. It is desirable that the edge faces of the slips 57 and the grooves 55 be dovetailed with relation to each other so that the slips 57 will not get out of place. The ring 64 is mounted for rotation on the upper end of the cage sleeve 63 and is held by a retaining ring 64a. At the lower end of the sleeve 63 cage springs 68 are mounted. These springs are secured to the lower end of the cage sleeve 63 by cap screws 69. The cage springs 68 are bowed outwardly. Their lower ends are fastened to a spring collar 70 by cap screws 71. The sleeve 63 is normally held against longitudinal movement by a bayonet joint comprising a nut or lug 79 extending outwardly from the mandrel and a bayonet slot 79a formed through the wall of the sleeve 63. A sub 72 is secured to the lower end of the mandrel section 60 and may receive another section of pipe.

In Fig. 5 of the drawing a packer structure is shown which embodies a new and novel structure in the form of a specially designed packer ring. In the use of ring packers it is desirable to eliminate the expense of placing the metal washers 48 between the rings 47. When this is done, however, it is found that the two end rings deform to a greater degree than the intermediate rings.

This seems to be for the reason that the end metallic faces 49 and 50 create direct pressure against the end rings and also create friction which prevents the portion of the ring directly in contact with the end faces from shifting outwardly so that a direct pressure is made against the central area of the outermost rings tending to expand and deform these two rings greatly. In the form of the rings shown in Fig. 5, the intermediate rings which are directly bearing against each other and the contiguous faces of the end rings will contact along rubber surfaces only. Observation of this action has proved that the two end rings expand to create a desired liquid seal but that the intermediate rings do not expand to such a great degree and thus there is not an effective seal throughout the length of the packer. In order to create uniform expansion of the packer rings and at the same time to eliminate the use of intermediate metallic washers, such as those indicated by the numeral 48 in the drawings, it has been found that if an annular groove 73 is cut in the wall of the bore through the ring at a point intermediate its length, so that opposite flat faces 75 and 76 are parallel to each other and normal to the axis of the packer, there will be uniform expansion of each of the rings, both with relation to each other and as to their individual contour. This will insure that a maximum sealing action will be obtained by all of the rings, and that a desired expansion will be produced without requiring the application of an abnormal weight on the packer.

In operation of the present invention, the packer structure is assembled which includes the rings and intermediate washers shown in Fig. 1 of the drawing or the rings with the internal annular groove such as shown in Fig. 5 of the drawing. A supporting string of pipe is then connected to the sliding head 10 by being threaded into the end section 12. The sliding head 10, with the valve sleeve 23 threaded thereon, is then rotated into locking engagement with the locking head 17 whereby the sliding head 10 and the mandrel 16 are held against relative axial movement with each other to normally hold the bypass valve open. In this position of the lock structure, as indicated in Fig. 4, the valve element 29 will be positioned above the valve seat element 42 and the valve will be opened. At this time the slip cone 53 will be in its uppermost position and thus the slips 57 will be in their lowermost positions within the grooves having tapered bottom faces 56.

It will be understood that due to the dovetail arrangement of the grooves and the sides of the slips the slips will remain within the grooves regardless of their longitudinal movement. When the slips are in this position the spring basket, which includes spring 68, will be in its lower position, and due to the fact that the bow of the springs is sufficient to cause the springs to extend outwardly and frictionally engage the contiguous casing wall, it is obvious that the springs will tend to retard downward movement of the packer and will allow it to become anchored when disposed at a desired level in the well.

When this level is reached the supporting drill string and the sliding head are rotated so that the locking head will move along the inclined keys 15 and so that the key segments 19 will fit within the keyways 14 formed in the sliding head. The mandrel 16 is held against rotation with the sliding head 10 by the springs 68, which resist rotation of the mandrel while permitting downward displacement thereof as the cam faces 15a are forced against the cam faces 22 until the key segments 19 are aligned with the keyways 14 and the splines 15 are aligned with the grooves 18. When thus aligned the sliding head may then be moved downwardly as the key segments travel along the keyways 14. As this downward movement takes place, the valve 29 will move into the bore 45 of the valve seat element 42 until it occupies a position within the bore 43, and the inclined face 30 of the valve

rests against the face 46 of the valve seat. When this takes place, the packing ring 28 will be within the large upper bore 45. Additional weight may then be placed upon the drill string and the sliding head. This weight will be directly applied to the face 46 of the valve seat by the face 30 of the valve. The result will be that the ring 28 will be compressed longitudinally and will be forced to expand laterally to form a tight seal against the wall of the bore 45. At this time the weight of the drill string will be imposed upon the valve seat element 42 which in turn will move the packing rings and the slip cone 53 downwardly while movement of the slips is resisted by friction occurring between the springs 68 and the side walls of the casing. The slips will thus stand stationary while the slip cone moves downwardly to force the slips outwardly into positive engagement with the side walls of the casing and to lock the slip cone so that it may not have any further downward travel. Up to this time the lower end of the packer sleeve 35 will be above the level of the ports 77 formed through the upper portion of the slip cone 53. After the slips are set, additional weight on the sliding head 10 will force the valve seat structure 42 downwardly, and will thus compress the packer rings 47 against the retaining nut 39. This will force the rings to expand laterally and to make a fluidtight seal with the casing 78.

Attention is directed to the fact that due to the construction of the bypass valve 29, his valve will form a seal between the tapered faces 30 and 46, and that in addition to this seal the packing ring 28 will expand within the bore 45 and form a further seal.

When the form of invention is used as shown in Fig. 6 of the drawing, the packing rings 47 will compress, and due to the fact that these rings are formed with the annular undercut groove 73, the central portion of the rings will tend to collapse and will cause the rings to be deformed and expanded so that they will increase in diameter uniformly and thus create a plurality of contacting faces with the well casing 78, and will bear against these faces with uniform pressure to create an efficient fluid seal. In the event it is desired to release the packer, the supporting string of pipe is elevated. This will pull the sliding head 10 upwardly and will cause the sliding head and locking head to move to disengaged positions. Attention is directed to the fact that when the sliding head 10 has been drawn upwardly to a point where it will lift the valve sleeve 23, the upper mandrel section 16 will be drawn upwardly and the slip cone 53 will be lifted to cause the slips 57 to be retracted from their engaging positions. Due to the construction of the locking head and the sliding head it is possible therefore to release the packer from its set position, and if desirable to reset it at any other level.

It will thus be seen that the packer construction here disclosed is simple and compact in its construction and provides an adequate area for permitting the bypass fluid to circulate as the packer runs into the well, the structure also providing means whereby the packer may be easily set and released, and when set, will produce an effective fluid-tight seal.

While we have shown the preferred form of our invention as now known to us, it will be understood that various changes may be made in combination, construction and arrangement of parts by those skilled in the art, without departing from the spirit of the invention as claimed.

Having thus described our invention, what we claim and desire to secure by Letters Patent is:

1. A well packer comprising a mandrel, a sleeve mounted over the mandrel intermediate its ends and having its inner wall spaced therefrom to provide a passage therewith, packing means carried by the sleeve, a valve seat upon the upper end of the sleeve, an actuating head slidably engaging the upper end of the mandrel and provided with valve means movable therewith axially of

the mandrel and sleeve from a normal unseated position spaced from said valve seat into seating engagement with the valve seat for closing the passage, a locking head upon the mandrel within the actuating head, interengaging splines and keyways upon the locking head and the actuating head, means for holding the splines of the actuating head normally in axial alignment with and seating upon the splines of the locking head to prevent downward axial movement of the actuating head relative to the mandrel, and means for moving the splines into alignment with their respective keyways in response to rotation of the actuating head.

2. A well packer comprising a mandrel, a sleeve mounted over the mandrel intermediate its ends and having its inner wall spaced therefrom to provide a passage therewith, packing means carried by the sleeve, a valve seat upon the upper end of the sleeve, an actuating head slidably engaging the upper end of the mandrel and provided with valve means movable therewith axially of the mandrel and sleeve from a normal unseated position spaced from said valve seat into seating engagement with the valve seat for closing the passage, a locking head upon the mandrel within the actuating head, interengaging splines and keyways upon the locking head and the actuating head, means for holding the splines of the actuating head normally in axial alignment with and seating upon the splines of the locking head for preventing downward axial movement of the actuating head relative to the mandrel, interengaging cam faces upon the abutting ends of the splines for urging the splines into alignment, and means for rotating the actuating head relative to said locking head to seat said valve.

3. A well packer comprising a mandrel, a sleeve mounted over the mandrel intermediate its ends and having its inner wall spaced therefrom to provide a passage therewith, packing means carried by the sleeve, a valve seat upon the upper end of the sleeve, an actuating head slidably engaging the upper end of the mandrel and provided with valve means movable therewith axially of the mandrel and sleeve from a normal unseated position spaced from said valve seat into seating engagement with the valve seat for closing the passage, a locking head upon the mandrel within the actuating head, interengaging splines and keyways upon the locking head and the actuating head, means for holding the splines of the actuating head normally in axial alignment with and seating upon the splines of the locking head for preventing downward axial movement of the actuating head relative to the mandrel, and inclined cam faces upon the lower ends of the actuating head splines engageable with recesses formed in the tops of the locking head splines and having correspondingly inclined cam faces for urging the splines into alignment, and means for rotating the actuating head relative to said locking head to move said splines into alignment with their respective keyways to permit downward movement of said actuating head relative to said locking head to seat said valve.

4. A well packer comprising a mandrel, a sleeve mounted over the mandrel intermediate its ends and having its inner wall spaced therefrom to provide a passage therewith, packing means carried by the sleeve, a valve seat upon the upper end of the sleeve, an actuating head slidably engaging the upper end of the mandrel and provided with valve means movable therewith axially of the mandrel and sleeve from a normal unseated position spaced from said valve seat into seating engagement with the valve seat for closing the passage, a locking head upon the mandrel within the actuating head, splines longitudinally disposed within the actuating head, each said spline having its lower end terminating in an upwardly inclined cam face, spline extensions having a width less than said actuating head splines extending downwardly

from said cam faces adjacent the upward end thereof, splines longitudinally disposed upon the locking head, said locking head splines being adapted to abut the actuating head spline extensions, said locking head splines being provided with recesses normally seating the lower ends of the actuating head splines and having inclined faces engaging the cam faces thereof, said faces being arranged to urge said locking head spline faces and actuating head spline faces into interengaging alignment and said locking head spline in abutting relation with said actuating head spline extension in response to downward thrust of said actuating head relative to said locking head, and means for rotating said actuating head relative to said locking head to move said splines into alignment with their respective keyways to permit downward movement of said actuating head relative to said locking head to seat said valve.

5. A well packer comprising a mandrel, a sleeve mounted over the mandrel intermediate its ends and having its inner wall spaced therefrom to provide a passage therepast, packing means carried by the sleeve, a valve seat upon the upper end of the sleeve, an actuating head slidably engaging the upper end of the mandrel and provided with valve means movable therewith axially of the mandrel, and sleeve from a normal unseated position spaced from said valve seat into seating engagement with the valve seat for closing the passage, a locking head upon the mandrel within the actuating head, interengaging splines and keyways upon the locking head and the actuating head, means for holding the splines of the locking head normally aligned with and seating upon the splines of the actuating head for preventing downward movement of the actuating head relative to the mandrel, means upon the abutting ends of the splines for moving the splines into alignment in response to downward movement of the actuating head relative to said locking head, means for rotating said actuating head relative to said locking head to move said splines into alignment with their respective keyways to permit downward movement of said actuating head relative to said locking head to seat said valve, and anchoring means secured to the lower end of the mandrel operable to provide an abutment against which the packing means may be com-

pressed and expanded upon the sleeve under downward force applied through the actuating head.

6. A well packer comprising a mandrel, a sleeve mounted over the mandrel intermediate its ends and having its inner wall spaced therefrom to provide a passage therepast, packing means carried by the sleeve, a valve seat upon the upper end of the sleeve, an actuating head slidably engaging the upper end of the mandrel and provided with valve means movable therewith axially of the mandrel, and sleeve from a normal unseated position spaced from said valve seat into seating engagement with the valve seat for closing the passage, a locking head upon the mandrel within the actuating head, splines longitudinally disposed within the actuating head, each said spline having its lower end terminating in an upwardly inclined cam face, spline extensions having a width less than said actuating head splines extending downwardly from said cam faces adjacent the upward end thereof, splines longitudinally disposed upon the locking head, said locking head splines being adapted to abut the actuating head spline extensions, said locking head splines being provided with recesses normally seating the lower ends of the actuating head splines and having inclined faces engaging the cam faces thereof, said faces being arranged to urge said locking head spline faces and actuating head spline faces into interengaging alignment and said locking head spline in abutting relation with said actuating head spline extension in response to downward thrust of said actuating head relative to said locking head, means for rotating said actuating head relative to said locking head to move said splines into alignment with their respective keyways to permit downward movement of said actuating head relative to said locking head to seat said valve, means secured to the lower end of the mandrel operable to resist rotative movement of the mandrel with the actuating head, and anchoring means secured to the mandrel below the sleeve operable to provide an abutment for the packing means.
